SHOE SOLE GRADING MACHINE

Charles C. Thomas, Medford, Mass., and Herbert W. Carnes, deceased, late of Swampscott, Mass., by Flora M. Carnes, executrix, Swampscott, Mass.

Continuation of application Serial No. 48,735, September 10, 1948. This application September 13, 1950, Serial No. 184,536

3 Claims. (Cl. 33—148)

1

This invention relates to grading machines of the class in which shoe soles, taps, and similar blanks of leather are subjected to conventional grading operations wherein the term "grading" may include skiving or evening a blank to a dimension corresponding to its thinnest section; also stamping or marking each blank with a character indicative of its thickness grade; and also indicating on a visible indicator the grades of various blanks, as well as sorting or classifying the blanks in accordance with their grade measurements.

In shoe making it is essential for best results in the completed shoe that the exposed edge portions of the sole or tap be of substantially uniform thickness, especially at the opposite side edges of the forepart of the sole. Actually, it is the thickness of relatively narrow marginal sections included along the opposite side edges of a sole which determine most accurately the thickness grade of the sole, and to which thickness the sole, as a whole, should be evened or skived down.

Difficulty has always been encountered in carrying out grading operations with caliper rolls so as to accurately deal with these irregular marginal side edge sections, since the latter not only vary in thickness, but deviate along two opposite curves, thus necessitating both vertical movement of the caliper rolls and some lateral movement to properly follow the contour of the edges and maintain a path of contact of substantially uniform marginal width. Such apparatus as has been devised to follow the marginal side edge sections is not practical to use and, as a result, there often occurs a certain amount of waste of leather removed in the skiving operation and, in some cases, there may develop failure to accurately skive the marginal edge sections to a thickness actually corresponding to the thinnest point therein.

The present invention is concerned with the problem indicated and aims to provide an improved apparatus for carrying out accurate edge measurements of a shoe blank without waste and without loss of accuracy in the skiving operation. Another object of the invention is to provide edge measuring mechanism which will measure only relatively narrow marginal sections of a blank; and which will follow the contour of a blank having an irregular or non-rectilinear side edge and will, therefore, measure a marginal area of substantially uniform breadth irrespective of the deviation of the side

2

edges of the blank. Another object of the invention is to provide edge measuring apparatus of the type described which may be adjusted to deal with a range of sole blank sizes and which may be operated in timed relationship with respect to the feeding of shoe blanks through the grading machine.

These and other objects and novel features will be more fully understood and appreciated from the following description of a preferred embodiment of the invention selected for purposes of illustration and shown in the accompanying drawings, in which

Fig. 1 is a full-sized development of two improved caliper rolls of the invention lying in spaced relation and presenting outer circumferential gauging surfaces which have been broken off for convenience. A shoe sole blank has been indicated in dot and dash lines in the position which it assumes when passing over the caliper rolls, and two additional horizontal dot and dash lines indicate the zone of grading along which the caliper action of the rolls is effective in positioning conventional setting mechanism and indicating mechanism in a grading machine;

Fig. 2 is a fragmentary side elevational view of a grading machine with which the improved edge measuring mechanism of the invention has been combined;

Fig. 3 is a cross-sectional view, partly in elevation, taken on the line 3—3 of Fig. 2, and in which view end portions of the grading mechanism have been broken off for convenience;

Fig. 4 is a detailed cross-sectional view taken on the line 4—4 of Fig. 3;

Fig. 5 is a plan view taken on the line 5—5 of Fig. 2;

Fig. 6 is a detail side elevational view of one of the shafts which support the rolls shown in Fig. 5;

Fig. 7 is a front elevational view of the gauging roll construction of the invention, further illustrating in cross-section a sole blank entered between the caliper rolls;

Fig. 8 is a view similar to Fig. 7 in which the gauging rolls have been rotated into a more advanced edge measuring position;

Fig. 9 shows a modified form of edge measuring or caliper roll in which a curved circumferential section is provided on the outer circumferential surface of the roll;

Fig. 10 is a vertical, cross-sectional view of another form of grading machine with which the gauge measuring mechanism of the invention

has been combined to provide for manual feeding of a shoe blank therethrough;

Fig. 11 is a front elevational view of a grading machine and edge measuring mechanism similar to that shown in Fig. 10 and indicating the position of the gauging rolls just prior to introduction of a sole blank thereon;

Fig. 12 is still another view of the apparatus shown in Figs. 10 and 11 and further indicating the gauging rolls in an operative position with a grading cycle and particularly showing one position of the clutch driving means;

Fig. 13 is a cross-sectional view, partly in elevation, taken on the line 13—13 of Fig. 11; and

Fig. 14 is a partial cross-section, in side elevation, taken on the line 14—14 of Fig. 11.

In accordance with the invention we have devised an improved blank feeding and gauging roll construction for grading machines. Included in the gauging roll construction is a pair of novel caliper rolls which constitute an upper set of rolls adapted to operate in conjunction with a lower set of detector rolls.

Essentially our improved caliper rolls comprise a pair of roll members arranged in spaced-apart endwise relation to one another with each roll being formed with a special circumferential edge measuring surface. The latter surfaces are designed to overlap relatively narrow opposite marginal edge sections of a leather blank in a predetermined manner so as to maintain paths of rolling contact of substantial uniform marginal width.

Each of the edge measuring surfaces is formed with an irregular inner boundary of definitely limited extent. The boundary terminates along a line which deviates in an axial direction as it extends circumferentially around its respective roll so as to form a curve substantially corresponding to the curvature of the particular side edge of a blank which it is designed to overlap.

Preferably these novel edge measuring surfaces are formed by relieving circumferential portions of the caliper rolls and the invention will first be described having reference to such a type of construction, combined with one standard form of grading machine in which conventional grading mechanism is utilized. It should be understood that the gauging roll construction of the invention either in the form about to be described in detail or in other forms, may be combined with and applied to a great many types of grading machines well known in the art, and is in no sense to be regarded as being limited to the single form of grading machine suggested in the drawings.

Referring more in detail to the drawings and especially to Figs. 2 and 3, we have illustrated a conventional form of grading machine, such as is disclosed in Pat. No. 2,325,011, issued to Metcalf in 1943. The structure shown in Figs. 2 and 3 is, in part, similar to the structure appearing in Fig. 6 of the Metcalf patent above mentioned.

In the drawings and specification of the present invention reference characters below numeral 100 are duplicates of numerals used in said Metcalf patent. The function of such parts is the same as in the patent referred to and since the operation of the grading mechanism is well known to the art and is clearly set forth in the patent referred to, no further detailed description will be furnished here other than to note that the gauging roll construction of the invention provides for a vertical roll displacement to actuate one or more pivoted arms connected to the members which move and set the grading mechanism

in varying desired positions of adjustment for skiving and other operations indicated above.

Considering in greater detail the gauging roll construction of the invention shown in Figs. 2 and 3, there is included therein a pair of upper caliper rolls having circumferential edge measuring surfaces 101 and 102. The rolls are fixed on a common drive shaft 3 rotatably supported at either end in two frame portions of the grading machine, as shown in the drawings. Each roll is secured by means of set screws, as 103 and 104, which engage in the respective grooves 105 and 106 to provide for adjustment of the caliper rolls toward or away from one another, as desired.

It should be understood that the extent of grading operations may vary in accordance with the type of sole blank grading. In utilizing the improved caliper rolls of the invention it should be borne in mind that grading the sole blank may, in some cases, as in any outer sole grading, take place over a portion only of the blank, as represented by the part included between the dot and dash arrow lines A and B of Fig. 1. The remaining portions of the blank, including the toe and heel sections, are not graded here as it is immaterial whether or not the thickness of any one of these portions falls below the minimum thickness occurring in the grading zone defined by arrows A and B.

In accordance with the invention, portions of the roll peripheries are relieved along two oppositely curved lines 101b and 102b to form the recessed areas 101a and 102a, as shown in Figs. 1, 7 and 8. It will be noted that these recessed areas constitute respective inner boundaries of the two opposite edge measuring surfaces 101 and 102. The curved lines 101b and 102b are selected with reference to the curvature of the side edge portions of the shoe blank B so that each edge measuring surface terminates along a line which deviates in an axial direction as it extends circumferentially around its respective caliper roll to form a boundary curve substantially corresponding to the contour of an adjacent curved edge of the blank, as suggested in Fig. 8.

It will readily be seen that by adjusting the caliper rolls toward or away from one another on the shaft 3 it is possible to take care of a range of blank sizes and to locate the respective boundary curves in any desired overlapping position with respect to marginal side edges of the blank B with the latter member being supported on the lower detector rolls 125—125 arranged in gauging relationship below the caliper rolls. There may thus be realized a position of register such that the overlapping must occur along a marginal area of approximately uniform width, as illustrated in Fig. 8.

The blanks are fed to the grading machine heel end first, and therefore the caliper rolls will be set to provide a margin of overlap which will be suitable for overlapping those opposite curved side edges occurring nearest the heel end of the blank. Actual feeding of the blanks may be carried out by hand feeding individual blanks, or by automatically feeding the blanks. In the structure shown in the drawings it is mandatory that the caliper rolls make one revolution only for each blank feeding and grading cycle. Other arrangements may be resorted to wherein, for example, the edge measuring surfaces of the invention are repeated around a single roll periphery.

Thus, in the apparatus illustrated in Figs. 2

and 3, for example, automatic feeding is provided for, as described in the Metcalf patent above referred to, with the single exception of a modified form of detector roll structure. In accordance with the invention the detector rolls 125-125 are mounted on pivoted levers 110 and 111 which are modified over the levers of the Metcalf patent by the provision of yoke ends 110a and 111a. A drive shaft 112 having a shouldered end 113 is adapted to engage in the yoke ends 110a and 111a, as shown in Fig. 3. The other end is shouldered and threaded to receive a wringer type gear 114 and nut 115. A key 116 engaging in the keyway of the gear 114 and a keyway located in the shouldered portion 15 of the shaft 112 securely engages the gear 114 with the shaft 112.

The gear 114 engages with a similar type gear 117 which is keyed at 118 to the main drive shaft 3. The drive on each of the lower rolls 20 and the upper drive shaft are identical, as are the shaft and internal parts of the lower rolls, the lower roll parts being interchangeable. On the main body of the lower roll shafts 112 we have provided a key member 119 on the end of 25 the shaft adjacent the gears 114.

Around the shafts 112 are journaled sleeve members 120. The sleeves 120 are provided with shouldered ends 121 which are journaled in the yoke portions 110a and 111a of the levers 110 and 111. In the shouldered end of the sleeves 121 we have provided recesses 122 comprising passages within which the key 119 of the shafts 112 turns without opposition, with exception of a key 123 or blocking member against which the 30 shaft key 119 engages under certain conditions, as will be explained further along in the specification.

The set screws 124 secure the sleeves 120 to the lower detector rolls 125-125 and it will be noted that the set screws 124 do not engage the shafts 112 but merely secure rolls 125 to the sleeves 120, the sleeve moving freely on the said shafts. In the position shown in Fig. 4 the shaft key 119 is engaged with the key portion 123 of the sleeve 120 which, in turn, is secured to the lower detector rolls 125. This is the relative position of the members of the lower detector roll assembly in a grading operation just prior to entry of the sole blank between the upper and lower sets of rolls.

It will be observed that the lower detector rolls are not rotating continuously but assume a position closely corresponding to that shown in Fig. 4. When the blank enters the nip of the rolls the upper caliper rolls are driven by the shaft 3 in a clockwise direction, as viewed in Fig. 4, and the blank then becomes a driving member operating against the rolls 125. The gears 114 and 117 stay in mesh without jamming but the key portion 123 moves away from the shaft key 119 on the sleeves 120. As soon as the blank passes out from the rolls the gears 114 and 117 again become effective and shaft key 119 moves around and engages the key portion 123, thereby turning the sleeve and the roll 125 until the rolls come to rest in the starting position shown in Fig. 4.

The upper caliper rolls may or may not turn continuously, depending on the particular construction of the specific driving mechanism in the rest of the grading machine. For example, the caliper rolls may turn at a constant rate of speed and the respective functions of the grading indicators and other skiving apparatus may be accomplished during the interval occurring between the time when upper caliper rolls 75

leave one blank and the time when they engage the next succeeding blank from the hopper H. This is merely a matter of driving ratio between the shaft 3 and other parts of the machine, involving well known engineering factors and not a part of the present invention.

In Figs. 10 to 14, inclusive, we have shown a further adaptation of the drive and caliper rolls to a manually fed grading machine which may or may not be included with skiving operations. This adaptation can be used with any one of numerous grading machines in which manual or semi-automatic construction is used. As viewed in Fig. 10, the main drive shaft 126 is engaged with the same wringer type gears already described by means of the keys 118 in the same manner illustrated in Fig. 3. The upper caliper rolls are identical with those previously noted and all mechanism in the lower detector roll construction is exactly the same as heretofore described.

A new and different structure is provided in connection with a timed cycle drive for the rolls and in the means for starting a grading cycle with a desirable cooperative relationship existing between the edge measuring surfaces 101 and 102 and the timed cycle drive. Another novel structure is provided in the take-off drive to related parts of the grading machine.

The timed cycle drive operates through intermediate gear 127 which is meshed with the gear 128 keyed at 129 to the main drive shaft 126. On the other end of the main drive shaft 126 there is provided an intermittent extension drive shaft 130 on which is keyed a gear 132 at point 131.

In operation, the extension shaft 130 is in continuous motion and the gear 132 may be connected with a motor drive or a belt driven pulley 40 may be substituted for the gear 132, or any other desired form of power coupling may be used. On the end of the shaft 126 is a special clutch member 133 being keyed to the shaft 126 by means of the key 134. The clutch member 133 is provided with an internal recess 135 and faced with a friction lining 136. The extension shaft 130 is journaled in a bracket 137 attached to the frame of the machine and has a shouldered body portion 138 and an internal recess 139 journaled around the reduced end 140 which is an extension of the main shaft 126.

Around the end of the shaft portion 140 adjacent the clutch portion 133 is a longitudinally slidable clutch cone 141 being slidable on the shaft member 133 by means of the key 142 fixed in the shaft extension member 140 and engaging in a slideway provided in the cone clutch member 141. The complete clutch is of the simple cone type, as shown in Fig. 10. Rotatably and slidably mounted on the shaft portion 133 is a yoke ring 143. Between the cone member 141 of the clutch and the ring 143 is a helical coil spring 144. The spring 144 normally maintains the ring out against the hub of the bracket 137 with insufficient pressure against the cone portion 141 to turn the clutch member 133 and shaft 126.

In this normal or neutral position the extension shaft 130 and clutch cone member 141 idles without any movement of the rolls 101, 102, or rolls 125. No movement of these rolls takes place until a sole blank is presented to the rolls for a grading operation.

Pivoted on a stud 145 mounted in an offset boss type bracket 146 which is fixed to the side of the

machine, is a lever hub 147 having laterally extended lever arms (see Figs. 11 and 12). The lever 148 operates the clutch mechanism and the lever 149 carries the trip mechanism which operates lever 148 and starts the machine on a grading cycle.

On the end of the lever 149 is an upwardly extended portion 150 and an inwardly extended portion 151, the end of which terminates in fork 152 between the sides of which is rotatably mounted a roll member 133. The roll 153 is positioned approximately midway between the two lower detector rolls and normally above the table surface 156 over which the blanks are fed so that when a blank is pushed over the trigger roll 153 and into the nip of the upper and lower gauging rolls the lever arm 149 is depressed and the rolls start to turn due to action set up by the movements of parts influenced by the lever arm 148 which will now be described in detail.

Lever arm 148 is turned up at approximately ninety degrees at 154 and again turns at ninety degrees to terminate in the upstanding yoke member 155 and yoke arms 156. The yoke arms 156 are provided with rolls 157 which engage in the annular groove 158 provided in the ring member 143. Branching off from the lever arm portion 154 is another horizontal arm 159 having a ninety degree upturned arm 160 which has a right-angled extension portion in the form of a yoke or fork member 161 within which is journaled a roll member 162. This apparatus is utilized to effect a timed operating cycle bearing a definite relationship to the edge measuring surfaces 101 and 102. Thus when the apparatus is in a normal position, as shown in Fig. 11, the roll 162 is at one end of a track 163 extending partway around the inner face of the outer flange of the clutch member 133. This position is in accordance with the invention chosen and constitutes the stop and start point of the rolls 101, 102 and 125 in making one complete cycle.

In operation, a blank of sole leather is pushed along the bed 154 of the machine over the trigger roll 153 into contact with the upper and lower gauging rolls. This operation depresses the trigger roll 153, tilting the lever 149 down and the lever 148 up. Simultaneously, the roll 162 is pulled out of the track 163 on the clutch member 133 from the position shown in Fig. 11, and the ring 143 is urged against the spring 144, causing the cone member 141 to frictionally engage the member 133, thereby starting the shaft 126 to rotate.

The wringer gears 117 on the shaft 126 engaging the wringer gears 114 on the shafts 112 of the lower rolls turns the lower rolls in a reverse direction, pinching the blank B therebetween and the start of the grading operation takes place. So long as the blank B is over the roll 153 the lower rolls continue to turn because the clutch members are engaged and the extension shaft 130, which is always in continuous operation, rotates the drive shaft 126. The overdrive feature of the lower rolls 125 permits these rolls to operate in the manner of idling gears without driving force being applied through the wringer gears 117 and 114.

The blank B progresses through the grading operation and beyond until the toe end of the blank passes over the trigger roll 153 which is approximately the point it leaves the rolls 101, 102 and 125. The blank is now passed to the skiving operation if the machine is provided with skiving

apparatus, an operation with which the present application is not concerned.

Upon the release of the trigger roll 153, the spring 144 forces the ring 143 back and depresses the lever arm 148, causing the roll 162 to press against the inner face of the clutch member 133 and drop into the track 163. The movement of the ring 142 backwardly and the dropping of lever arm 148 does not take place immediately when the sole blank B leaves the roll 153 or until the roll 162 reaches a point permitting it to drop into the track 163. This point is slightly in advance of the stopping point 175 during which time the detector rolls are finishing their cycle. During this period after the blank B leaves the detector rolls, the gears 117 and 114 are again active and the lower roll shafts 112 rotate faster than shaft 126, causing the key member 119 to catch up with the key member 123, at which time the rolls 125 are driven by the gears 114.

During the time that the spring 144 is compressed to a maximum degree, the roll 162 turns on the face of the clutch portion 133. At the point at which the blank B moves out of contact with the roll 153, the full force of the spring 144 is exerted on the roll 162 and shortly thereafter the roller 162 drops into the track 163 and before the caliper rolls have continued to rotate and reach a point corresponding nearly to the starting point of the cycle. Actually a very short movement of the rolls must take place after the roller 162 drops into the track 163 and before the roll 162 comes to rest against the abutment 175 at the end of the track.

In accordance with the invention the several parts referred to are so constructed and arranged as to control the short movement of the rolls after the blank moves away from the nip point. Specifically, the movement is controlled so that those parts of the edge measuring surfaces 101 and 102, first contacting the shank end of a blank, will lie in a predetermined relationship to those points at which the inner curved boundary lines 101b and 102b start to deviate and, therefore, the curved edges may be brought into register with the corresponding curved edge portions of the blank B.

There is thus achieved a timed cycle of operation by which the curved boundaries of the edge measuring surfaces may be registered with correspondingly curved edge portions of the blank and this relative positioning may be successively repeated with precision and accuracy over a repeated number of cycles of operation without material deviation.

The practical application of the novel curved edge measuring surfaces of the invention, therefore, may be realized to the fullest extent with attendant advantages in the actual gauging operation so that gauging is confined to marginal edges of uniform width in the manually fed operation.

The stopping of the roll 162 against the abutment at 175, above referred to as the stopping point, abruptly terminates the rotation of the rolls 101 and 102. The dwell or track 163 in the clutch member 133 may be only of limited length or may be extended, as desired, to suit varying conditions determined by the blank and the portions of the blank which are to be gauged. When the clutch friction surfaces are released from contact with one another, the extension shaft 130 and gear 132 continue to rotate in the same manner as before the clutch became engaged.

Our new type caliper rolls, with particular

reference to the upper curved track rolls, is ideally suited for a certain brand of square cut soles. It is not necessarily limited to such soles, however. A range of sizes are cut with the same curved knife in a certain conventional machine, hence all sizes of this type of blank have the same curve or swing. To change sizes on a machine using our improved caliper rolls, a simple adjustment of the lateral spacing of the upper rolls is all that is necessary. In any event, an assortment of a very few rolls would probably cover the entire field.

It should be borne in mind that perfectly cylindrical rolls of the proper diameter may be used, such as the roll illustrated in Fig. 9, indicated by 15 the numeral 180, and a curved strip 181 may be attached to the circumference of the roll 180 to produce the same effect as in rolls 101 and 102. The strip 181 may be integral with, or separate from the roll 180. Rolls 101 and 102 may be relieved along the whole face of the roll instead of only for a certain depth below the curved edge, and various other types of construction may be resorted to in forming the novel curved edge 20 measuring surface of these rolls.

We have shown two types of uses for these new caliper rolls, such as in a semi-automatic machine and in mechanism in combination with the curved rolls adapted for use with old type grading machines, and it is to be understood that 25 while we have shown combined mechanism in use with the new rolls, yet the scope of the invention may be much broader, limited only by the scope of the appended claims. This application is a continuation of copending application Ser. 30 No. 48,735, filed September 10, 1948 and now abandoned.

Having thus described our invention, what we desire to claim as new is:

1. An improved grading machine for grading 40 a shoe sole blank having opposite curved side edges included in the forepart, thereof, said grading machine comprising a pair of detector rolls in endwise spaced apart relationship, a second pair of caliper rolls located above the detector rolls in suitable gauging relationship to receive the sole blank therebetween, said caliper rolls being formed with circumferential edge measuring surfaces adapted to overlap marginal edges of the forepart of the sole blank, each of 45 said edge measuring surfaces terminating along a line which deviates in an axial direction as it extends circumferentially around its respective

5
10

caliper roll thereby to form a curve substantially corresponding to the contour of an adjacent curved edge of the forepart of the sole blank, and said machine further including independently driven shafts for the detector roll, gear means for driving the shafts in response to rotation of the caliper rolls, each of the detector rolls being operatively connected to its respective shaft by means of a sleeve member, said sleeve members being mounted about their respective shafts for rotation through a limited arc of rotation.

2. An improved grading machine for grading a shoe sole blank having opposite curved side edges included in the forepart thereof, said grading machine comprising a pair of detector rolls in endwise spaced apart relationship, a second pair of caliper rolls located above the detector rolls in suitable gauging relationship to receive the sole blank therebetween, said caliper rolls being formed with circumferential edge measuring surfaces adapted to overlap marginal edges of the forepart of the sole blank, each of said edge measuring surfaces terminating along a line which deviates in an axial direction as it extends circumferentially around its respective caliper roll thereby to form a curve substantially corresponding to the contour of an adjacent curved edge of the forepart of the sole blank, and said machine further including independently driven shafts for the detector rolls, gear means for driving the shafts in response to rotation of the caliper rolls and mechanism for operatively connecting the detector rolls to their respective shafts in one position of rotation thereof.

3. A structure according to claim 2, including means for rotating the detector rolls at a relatively faster rate of speed than the respective detector roll shafts when the shoe sole blank is passing between the caliper rolls and the detector rolls.
